UNITED STATES PATENT OFFICE.

ALMOND D. DURHAM, OF DENVER, COLORADO.

INTERNAL-COMBUSTION ENGINE.

1,297,118.

Specification of Letters Patent. Patented Mar. 11, 1919.

Application filed February 20, 1918. Serial No. 218,182.

To all whom it may concern:

Be it known that I, ALMOND D. DURHAM, a citizen of the United States, residing in the city and county of Denver and State 5 of Colorado, have invented certain new and useful Improvements in Internal-Combustion Engines; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention relates to improvements in internal combustion engines, my object being to provide a construction in which the piston pressure area is increased as compared with the diameter of the cylinders in which the 20 piston is located, the cylinder being provided with an abutment between its extremities perforated to receive a tube, to the opposite extremities of which are attached heads which with the tube constitute 25 the piston. The explosive mixture is simultaneously introduced into the cylinder on opposite sides of the cylinder abutment and is compressed by both heads of the piston, one head compressing the mixture between 30 itself and the upper or outer extremity of the cylinder, while the other head compresses the mixture between itself and the cylinder abutment. The explosive mixture while ignited at the upper extremity of the 35 cylinder is virtually exploded simultaneously in contact with both heads of the piston, whereby the explosive force acts upon substantially or approximately a double surface area, thus making it practicable 40 to greatly increase the power of the engine for a given diameter of the cylinder.

Any suitable means may be employed for controlling the intake and exhaust as nothing is claimed on this mechanism.

45 Having briefly outlined my improvement, I will proceed to describe the same in detail, reference being made to the accompanying drawing, in which is illustrated an embodiment thereof. In this drawing:

50 Figure 1 is a view partly in elevation and partly in central, longitudinal section cutting one of the cylinders and the corresponding part of the crank case.

Fig. 2 is a cross section taken on the line 55 2-2, Fig. 1, looking downwardly.

Fig. 3 is a central vertical section of the engine taken on the line 3-3, Fig. 1 looking toward the left.

The same reference characters indicate the same parts in all the views. 60

Let the numeral 5 designate a cylinder of my improved engine, and as each cylinder is a substantial duplicate of every other cylinder, a description of one will be a description of all. This cylinder is provided at its extremities with a partition or abutment 6 which, as illustrated in the drawing, is formed integral with the lower cylinder member 7, the upper cylinder member 8 being connected with the lower 70 cylinder member by bolts 9 passing through abutting flanges 10 formed on the two cylinder members. The abutment 6 is perforated, as shown at 4, to receive a tube 12 to one extremity of which is secured a 75 piston head 13, as shown at 14, while to its opposite extremity is secured a piston head 15, which as shown in the drawing is formed integral with the tube. The two piston heads 13 and 15 are suitably spaced 80 and occupy positions on opposite sides of the abutment 6 of the cylinder. This is a four cycle engine. Let the numeral 16 designate a valve for controlling an intake port 17 which is in communication with a 85 conduit 18 for supplying explosive mixture to the engine. Provision is made for mechanically opening the intake valve 16 of each cylinder at properly timed intervals to allow the entrance of a charge of mixture for each four strokes or two complete reciprocations of the piston. The valve 16 is normally held in the closed position by a spiral spring 53, a similar spring 19 being located between a shoulder 20 and a 90 tension nut 21 threaded on the valve stem 22, the lower extremity of the stem being bifurcated, as shown at 23, to receive a gear 24 which is eccentrically journaled in the arms of the bifurcation, the gear being arranged to turn on a journal located beyond the center of the gear, whereby a cam action is secured for the purpose of obtaining the opening and closing movement of the valve 16. As this is a four cycle engine, only one opening movement of the valve should occur during each two complete reciprocations of the piston or complete rotations of the crank shaft 25. Hence, the shaft is provided with a small 110

2
gear 26 whose circumference is half that of the gear 24. Consequently, the desired movement of the valve 16 is obtained, the spring 19 being under tension to maintain the gears 24 and 26 in mesh, while the bifurcated gear-holding extremity of the valve is slotted at right angles to the bifurcation in which the gear is located to allow the valve the necessary reciprocating movement. Attention is called to the fact that no effort will be made to explain the valve motion in detail, as nothing is claimed thereon in this application. Furthermore, any suitable mechanism may be employed 15 for controlling the intake valve.

The valve 16 opens into a passage 27 which communicates through a port 28 with the upper extremity of the cylinder. The cylinder is also provided with an exhaust port 29 communicating with a passage 30 which is in communication by a port 31 with an exhaust passage 32 which may communicate with the atmosphere through a conduit of any desired character. As shown 25 in the drawing (see Fig. 1) the exhaust conduit which is chiefly broken away, is designated by the numeral 33, its communication with the exhaust passage 32 being cut away on the sectioned side of the view. In 30 this view it must be assumed that the exhaust conduit 33 is arranged in front of the cylinders and the intake conduit 18 in the rear. The exhaust valve or the valve for controlling the exhaust port 31 is designated 35 by the numeral 34 and is provided with a stem 35 having a tension nut 36 between which and the shoulder 37 is located a spiral spring 38, a similar spring 52 normally holding the valve in the closed position, 40 while the spring 38 maintains the gears 39 and 40 in mesh, the gear 39 being arranged between the two arms of the bifurcated extremity 41 of the valve stem, the gear being pivoted, as shown at 42, beyond its center, 45 the bifurcation 41 being slotted to receive the crank shaft and to permit the necessary reciprocating movement of the valve stem for valve opening and closing purposes. The construction for operating the exhaust 50 valve is substantially the same as that used for operating the intake valve, which has heretofore been described in detail. The lower head or member 15 of the piston is connected by means of a pitman 43 with a 55 crank 44 of the crank shaft. The upper compartment 45 of the cylinder is in communication with the atmosphere between the piston head 13 and the abutment 6 by means of perforations 46, thus preventing 60 either compression or a vacuum condition in the cylinder between the head 13 and the abutment during the intake and compression strokes respectively. As the lower or inner extremity of the cylinder is in communication with the crank case, the com- 65

pression or vacuum condition at this end of the cylinder will be negligible.

From the foregoing description the use and operation of my improved engine will be readily understood. Assuming, referring first to Fig. 1, that the piston is moving downwardly or inwardly toward the crank case and that a charge of explosive mixture is being drawn into the cylinder, both in the upper compartment 45 and into 75 the lower compartment which I will designate by the numeral 48, the said charge of mixture entering the cylinder initially through the port 28, but passing freely not only into the compartment 45 but also 80 through the tube 12 of the piston and perforations 49 formed therein, into the compartment 48; now, as the piston begins its upward or outward stroke, the intake valve 16 will be closed and the explosive mixture 85 will be compressed between the outer head 50 of the cylinder and the piston head 13, and also between the piston head 15 and the abutment 6 of the cylinder. Now, as soon as the piston has reached the limit of its 90 outward stroke, the explosive mixture will be ignited initially at the outer extremity of the cylinder, but this ignition will for all practical purposes, occur in both compression compartments or between the piston 95 head 13 and the cylinder head 50 and between the abutment 6 and the piston head 15. Consequently, the explosive force will act simultaneously upon both piston heads to drive the piston inwardly toward the 100 crank case. As soon as the piston has reached its inward limit of movement and starts upon its outward stroke, the exhaust valve 34 will be opened and the cylinder will be scavenged of its refuse burned products of combustion, those in the compartment 45 passing directly through the exhaust port and passages while that in the compartment 48 is expelled through the perforations 49, the tube 12 and the compartment 105 45. From this it will be understood that I obtain from my improved construction great power relatively, considering the diameter of the cylinder, by reason of the fact that the piston is of such construction 110 that nearly twice the area is exposed to the action of the explosive force as compared with other structures having the same diameter of cylinder.

Attention is called to the fact that this 120 same cylinder and piston construction may be advantageously employed in steam engines and pumps which will be covered by simultaneously pending applications.

Attention is called to the fact that the 125 stems 22 and 35 for controlling the intake and exhaust valves respectively are divided so that each valve may be quickly opened to its full extent rather than opened too gradually as might be the case if the said stems 130

22 and 35 were integral. As now constructed, the upper extremity of each stem acts upon a short stem member with which the valve piece is directly connected, the 5 spiral springs 53 and 52 respectively serving to normally maintain the valve pieces in the closed position. This action of the upper extremity of the stem 22 or 35, as the case may be, occurs as the stem is approaching its upward limit of movement, thus 10 making the opening movement of the valve rather instantaneous than gradual. But, as heretofore stated, the invention is not limited to any specific mechanism for controlling the intake and exhaust.

15 Attention is called to the fact that in my improved construction the intake space for explosive mixture is approximately double for the same length of piston stroke, what 20 it is in an ordinary engine with the same size cylinder.

25 The head 50 of each cylinder, as illustrated in the drawing is provided with a spark plug 51 of ordinary construction and which may be utilized in properly timing the explosions through the instrumentality of ignition mechanism (not shown).

Having thus described my invention, what I claim is:

30 1. An engine including a cylinder closed at one end and provided with an abutment intermediate its extremities, and a piston reciprocable therein and including spaced heads arranged on opposite sides of the cylinder abutment, the structure having a permanently open passage connecting the space between the closed end of the cylinder and one head of the piston with the space between the opposite head of the piston and the abutment of the cylinder, each of said 35 spaces constituting a combustion chamber.

40 2. The combination of a cylinder having one head and an abutment, the latter being arranged between the extremities of the cylinder and a piston reciprocable in the cylinder and composed of two connected heads spaced to occupy positions on opposite sides of the abutment, and a passage communicating at one extremity with the space between the cylinder head and one head of the piston and at its opposite extremity with the space between the opposite piston head and the cylinder abutment, said passage extending through the piston and its rod.

45 55 3. The combination of a cylinder having one head and an abutment, the latter being arranged between the extremities of the cylinder, and a piston reciprocable in the cylinder and composed of two connected heads spaced to occupy positions on opposite sides of the abutment, a passage communicating at one extremity with the space between the cylinder head and one head of the piston and at its opposite extremity with the space 60 between the opposite piston head and the

cylinder abutment, and means for simultaneously introducing motive fluid to both of said spaces.

4. An internal combustion engine including a cylinder having a closed head, and an abutment arranged between its extremities, a piston mounted to reciprocate therein and including two spaced heads arranged on opposite sides of the cylinder abutment, said heads being connected to move in unison, a 70 passage having one extremity in communication with the space between one head of the piston and the closed end of the cylinder, while the other extremity of the passage communicates with the space between the opposite head of the piston and the cylinder abutment, each of said spaces constituting a combustion chamber, and said passage extending through the piston and its rod.

75 5. An internal combustion engine including a cylinder having a closed head, and an abutment arranged between its extremities, a piston mounted to reciprocate therein and including two spaced heads arranged on opposite sides of the abutment, said heads being connected to move in unison, a passage having one extremity in communication with the space between one head of the piston and the closed end of the cylinder, while the other extremity of the passage communicates with the space between the opposite head of the piston and the cylinder abutment, each of said spaces constituting a combustion chamber, and said passage 80 extending through the piston and its rod.

85 90 6. An internal combustion engine including a cylinder having a closed head, and an abutment arranged between its extremities, a piston mounted to reciprocate therein and including two spaced heads arranged on opposite sides of the abutment, said heads being connected to move in unison, a passage having one extremity in communication with the space between one head of the piston and the closed end of the cylinder, while the other extremity of the passage communicates with the space between the opposite head of the piston and the cylinder abutment, and means for simultaneously introducing explosive mixture to both of said 95 spaces.

100 105 7. The combination of a cylinder having a closed head, and an abutment arranged between its extremities, a piston mounted to reciprocate therein and including two spaced heads arranged on opposite sides of the abutment, said heads being connected to move in unison, a passage having one extremity in communication with the space between one head of the piston and the closed end of the cylinder, while the other extremity of the passage communicates with the space between the opposite head of the piston and the cylinder abutment, means for simultaneously introducing explosive mixture to both of said 110 spaces, and means for simultaneously igniting such mixture in both of said spaces.

115 120 8. The combination of a cylinder closed at one end and having an abutment approximately midway between its extremities, a piston mounted to reciprocate in the cylinder and including two connected spaced heads arranged on opposite sides of the abutment and forming explosion compartments respectively located between one piston head 125 and the closed end of the cylinder and between the other piston head and the cylinder abutment, a passage connecting the explosion compartments, means for simultaneously introducing explosive mixture to both 130

compartments, and means for simultaneously igniting such mixture in both compartments.

8. The combination of a cylinder closed at one end and having an abutment located approximately midway between its extremities, a piston mounted to reciprocate in the cylinder and including two connected spaced heads arranged on opposite sides of the abutment and forming explosion compartments between one piston head and the

closed end of the cylinder, and between the other piston head and the abutment, and a permanently open passage connecting the two explosion compartments, the cylinder ¹⁵ being provided with intake and exhaust ports controlled to open and close at properly timed intervals to operate on the four cycle principle.

In testimony whereof I affix my signature. 20

ALMOND D. DURHAM.
